DESIGN FOR A HELICOPTER TOY

Theodore Phagen, Long Island City, N. Y.

Application May 10, 1946, Serial No. 129,566

Term of patent 3½ years

(Cl. D34—15)

To all whom it may concern:

Be it known that I, Theodore Phagen, a citizen of the United States, residing in Long Island City, county of Queens, State of New York, have invented a new, original, and ornamental Design for a Helicopter Toy, of which the following is a specification, reference being had to the accompanying drawing, forming a part thereof, in which:

Fig. 1 is a plan view of my new design of a helicopter toy;

Fig. 2 is a side elevational view thereof, and
Fig. 3 is a front elevational view thereof.

The essential feature of my design resides in the portion shown in full lines on the drawing.

I claim:

An ornamental design for a helicopter toy, as shown and described.

THEODORE PHAGEN.
